CLAIM

The ornamental design for an electronic computer, as shown and described.

DESCRIPTION

FIG. 1 is a top front right side perspective view of an electronic computer showing my new design;
FIG. 2 is a front elevational view thereof;
FIG. 3 is a rear elevational view thereof;
FIG. 4 is a top plan view thereof;
FIG. 5 is a top plan view thereof showing the display panel in the closed position;
FIG. 6 is a top plan view thereof showing the display panel in an opened and rotated position;
FIG. 7 is a bottom plan view thereof;
FIG. 8 is a left side elevational view thereof;
FIG. 9 is a right side elevational view thereof;
FIG. 10 is a right side elevational view thereof, the display panel in the closed position;
FIG. 11 is a top front right side perspective view of a second embodiment of my new design;
FIG. 12 is a front elevational view thereof;
FIG. 13 is a rear elevational view thereof;
FIG. 14 is a top plan view thereof;
FIG. 15 is a top plan view thereof showing the display panel in the closed position;
FIG. 16 is a top plan view thereof showing the display panel in an opened and rotated position;
FIG. 17 is a bottom plan view thereof;
FIG. 18 is a left side elevational view thereof;
FIG. 19 is a right side elevational view thereof; and
FIG. 20 is a right side elevational view thereof showing the display panel in the closed position.

FIG. 1***FIG. 2******FIG. 3******FIG. 4*****FIG. 5****FIG. 6*****FIG. 7******FIG. 8******FIG. 9******FIG. 10*****FIG. 11****FIG. 12*****FIG. 13******FIG. 14*****FIG. 15****FIG. 16*****FIG. 17******FIG. 18****FIG. 19*

FIG. 20
